UNITED STATES PATENT OFFICE

90,750

DESIGN FOR AN AUTOMOBILE RADIATOR ORNAMENT OR SIMILAR ARTICLE

Casimer L. Cislo, Detroit, Mich., assignor to
Ternstedt Manufacturing Company, Detroit,
Mich., a corporation of Michigan

Application January 11, 1933. Serial No. 46,786

Term of patent 7 years

To all whom it may concern:

Be it known that I, CASIMER L. CISLO, a citizen of the United States, residing at 4172 Thirtieth Street, Detroit, in the county of Wayne and State of Michigan, have invented a new, original, and ornamental Design for an Automobile Radiator Ornament or Similar Article, of which the following is a specification, reference being made of the accompanying drawing forming part thereof.

Fig. 1 is a side elevation of an automobile radiator ornament or similar article, showing my new design;

Fig. 2 is a plan view of the same.

I claim:

The ornamental design for an automobile radiator ornament or similar article substantially as shown.

CASIMER L. CISLO.
